(57) **CLAIM**

The ornamental design for a endotracheal intubation device, as shown and described.

DESCRIPTION

FIG. 1 is a front, right perspective view of a endotracheal intubation device showing our new design;

FIG. 2 is another front, right perspective view thereof;

FIG. 3 is a front elevation view thereof;

FIG. 4 is a rear elevation view thereof;

FIG. 5 is a right side elevation thereof;

FIG. 6 is a left side elevation view thereof;

FIG. 7 is a top plan view thereof; and,

FIG. 8 is a bottom plan view thereof.

The dashed broken lines in the Figures show portions of the endotracheal intubation device that form no part of the claim. The dashed-dotted broken lines in the Figures define the boundaries of the claimed design and form no part thereof.
